UNITED STATES PATENT OFFICE.

CHARLES W. WITTINGTON, OF HAVERHILL, MASSACHUSETTS, ASSIGNOR TO
WITTINGTON & ROYAL, OF SAME PLACE.

DESIGN FOR A DUST-GUARD FOR CORNERS.

SPECIFICATION forming part of Design No. 30,684, dated May 2, 1899.

Application filed March 18, 1899. Serial No. 709,601. Term of patent 7 years.

To all whom it may concern:

Be it known that I, CHARLES W. WITTINGTON, a citizen of the United States, residing at Haverhill, in the county of Essex and State 5 of Massachusetts, have invented a new and useful Design for Dust-Guards for Corners, of which the following is a specification.

The object of this invention is to provide a new and original design for dust-guards for 10 corners.

The drawings accompanying this specification give and convey to those skilled in the art a clear understanding of the design and is sufficient to enable such persons to use the 15 same.

In said drawings, Figure 1 is a front view of a dust-guard for corners embodying the design, and Fig. 2 is a central sectional view of the same.

The design consists of a substantially triangular beveled-edged dust-guard having curvature in two directions, forming what may be termed a "warped" surface, having a concaved lower edge and convexed sides.

What I claim as my invention, and desire 25 to secure by Letters Patent of the United States, is—

The design for a dust-guard for corners, substantially as shown.

In testimony whereof I have hereunto set 30 my hand in the presence of two subscribing witnesses.

CHARLES W. WITTINGTON.

Witnesses:

CHARLES W. ROYAL,
JOSEPH H. PEARL.
